STRAIGHT EDGE
Arnold Aisen, 14037 W. 7-Mile Road, Detroit, Mich.
Filed Mar. 23, 1962, Ser. No. 182,050
1 Claim. (Cl. 33—107)

This invention relates to a straight edge and more particularly to a straight edge or rule type member, particularly adapted for marking and cutting of glass, but also adapted for the cutting or making of metal, linoleum, or other planar objects.

Heretofore, in the manufacture of rules and straight edges, such as used in the glass trade, for example, the opposing upright edge faces of the rule wear or become damaged, or otherwise marked up, with the result that the rule or straight edge must be repaired or replaced. These straight edges are extremely expensive, particularly the long ones, and may range from 6 to 20 feet in length. Oftentimes when it is necessary to repair these straight edges, it is necessary to return them to the factory for a 10 refinish of the edge faces thereof.

It is therefore the primary object of the present invention to provide a novel form of straight edge, preferably constructed of an aluminum body, and wherein the edge faces upon opposite sides thereof are formed of removable and replaceable plastic or nylon members which interlockingly engage the opposing edges of the straight edge, and which when worn or damaged, may be easily replaced.

It is another object of the present invention to provide a straight edge which is non-warping in character, and wear of the edge faces is minimized by the construction of the movable edge strip, preferably constructed of nylon, and wherein also the edge strips for the straight edge project beyond the edge faces of the said straight edge for contact with the glass, or other surface to be marked, or cut, and to thus prevent scratching of the glass or other material.

It is another object of the present invention to provide in a straight edge preferably of metallic construction such as aluminum, a replaceable and interchangeable and removable edge strip of nylon which directly interlocks with the body of the straight edge and when assembled provides a smooth continuation thereof.

It is a further object of the present invention to provide a straight edge which will have a minimum contact with the glass surface to be marked or cut, and wherein there is no metal contact with the glass.

It is a further object to provide removable edge strips for the straight edge of nylon or other hard plastic material to minimize frictional engagement of the glass or other surface and which will facilitate sliding of the straight edge thereover.

It is another object of the present invention to provide removable and replaceable edge strips for the straight edge which have upright edge faces of increased height against which the cutting tool is guided.

It is another object of the present invention to provide a straight edge constructed of extruded aluminum and which incorporates undercut or dovetailed grooves or slots in the top surface thereof within which is removably inserted an elongated glass breaking member.

It is another object of the present invention to form in the top surface of the rule, an elongated guide groove for cooperation with means for retaining a cutting tool and at all times along the upright edge face of an edge strip of the straight edge to facilitate the cutting of glass or other objects and for maintaining the cutting tool against the straight edge throughout the length of the said straight edge.

It is a further object of the present invention to provide in the present straight edge a series of longitudinally

2

spaced suction cups providing a means of anchoring the straight edge to a glass or other surface and with means incorporated in conjunction with the said suction cups for effecting a manual release thereof.

It is a further object of the present invention to adapt a removable and replaceable plastic edge strip to a T-square construction, or a triangle, or a right-angle square.

These and other objects will be seen from the following specification and claims in conjunction with the appended drawings in which:

FIG. 1 is a plan view of the present straight edge as mounted upon a strip of glass, fragmentarily shown.

FIG. 2 is a front elevational view thereof.

FIG. 3 is a section taken on line 3—3 of FIG. 2, on an increased scale.

FIG. 4 is a section taken on line 4—4 of FIG. 2, on an increased scale.

FIG. 5 is a plan view of the present straight edge with suction cups incorporated therewith and including an indicia strip.

FIG. 6 is a fragmentary section taken on line 6—6 of FIG. 5 on an increased scale.

FIG. 7 is a fragmentary section taken on line 7—7 of FIG. 6.

FIG. 8 is a plan view of a T-square incorporating the present invention.

FIG. 9 is a fragmentary plan view of a right angle square incorporating the present invention.

It is contemplated that the drawings illustrate merely a preferred embodiment of the invention and that other embodiments may be provided within the scope of the claims hereinafter set forth.

Referring to the drawings, and with particular reference to FIGS. 1 through 4, the present straight edge includes an elongated hollow body, generally indicated at 11, preferably formed of extruded aluminum and which includes elongated flat top surface 12, and a corresponding bottom surface 13. The body includes adjacent its opposite edges elongated webs 14 and 15 and adjacent to which are formed elongated undercut or dovetailed grooves or slots 16 which extend throughout the length of the body along and adjacent its opposite edges 19.

Elongated, preferably non-metallic edge strips 18, with outer straight upright edge faces are mounted along the opposing upright side edges 19 of the straight edge body and are removably interlocked therewith, as best shown in FIGS. 3—4.

For this purpose, formed elongated projections, preferably of dovetailed shape, as at 17, extend laterally from the inner surfaces of the said strips 18 and are adapted to snugly and retainingly project within the correspondingly shaped dovetailed grooves 16, formed in the opposite edges of the said body.

The edge strips 18 are preferably constructed of a plastic material which is hard and which has good wear characteristics such as nylon, and wherein the said edge strips 18 are assembled longitudinally with respect to the dovetailed slot 16 in the edge faces of the body, and an interlock is provided, as shown.

Upright edge faces of the said edge strips are of a height greater than the height of the body 11, and accordingly project above the top surface 12 and below the bottom surface 13, as shown in FIG. 4, and as at points 20, thus spacing the undersurface of the body, as at 21 from the glass G, upon which the straight edge is mounted, for illustration.

By this construction, a non-metallic nylon edge strip 18 actually supports the metal body of the rule, or straight edge above the said glass, or other surface and thus prevents any possible scratching thereof, and at the same

time facilitates adjustments of the straight edge over the glass surface.

Closure end strips are also provided for the body, as shown in FIGS. 1, 2 and 3.

Elongated end strip 22, preferably constructed of plastic, rubber, or other resilient material, extends across one end face of the said body and includes the formed tongue 23, which is frictionally projected into the end of the body and retained therein, as shown in FIGS. 1 and 2.

An additional end strip 24 is provided for the opposite end of the body which is of a slightly different formation and also includes a tongue which is so formed as indicated at 25, FIG. 3, as to be frictionally and snugly projected within the opposite end of the body, and retained therein. The said end strip along its lower transverse edge projects below the said body as at 26, and thus provides a stop for the straight edge, retainingly engaging the corresponding edge of a piece of glass G, over which the straight edge is mounted, the stop being indicated at 27, FIG. 2.

Similarly the end strip 24 projects above the top surface of the body as indicated at 28. The end strips are preferably constructed of rubber, or a suitable non-metallic, preferably plastic, material, to avoid damage to the glass or other surface being cut, or marked.

As shown in FIG. 3, the top surface 12 of the body 11 has an additional extruded formation, as at 29 to thus define the elongated guide slot 30, which extends throughout the length of the top surface of the body, and parallel to the edge strips and is employed for the purpose of guidably retaining the glass cutter 35 with respect to the upright surface of the adjacent edge strip 18, as best shown in FIG. 4.

The roller 31 movably nests within the guide slot 30, and is journaled at 32 to the bracket or support 33 which is itself secured or pivotally connected at 34 to glass cutter 35, carrying the diamond or other hardened glass cutting wheel 36.

It is the primary object of this construction to provide the guide means 30-31 for the purpose of maintaining the cutting tool 35 snugly against the upright surface of the corresponding edge strip 18. This means that the operator is not required to exert effort to maintain the cutter against the said edge strip and may thus exert all of his effort for a uniform longitudinal marking or cutting movement along the top surface of the glass G, or other surface.

The present straight edge also has incorporated thereinto a means for breaking glass once it has been cut. For this purpose the body has an extruded formation 37 adjacent the top surface 12 thereof, as shown in FIG. 4 to define an undercut elongated slot 38, preferably of dovetail shape in cross section, adapted to removably receive and interlock with a correspondingly shaped projection 39 formed in the undersurface of the elongated glass breaker strip 40, which is preferably constructed of nylon.

In accordance with the present invention, the glass plate breaker strip, which is square in cross section, to provide the elongated corners shown in FIG. 3, is of the same construction as the removable side edge strips 18.

In the use of the glass breaker, once the glass has been cut, as shown in FIG. 4, the glass breaker strip 40 and associated straight edge is placed directly under glass and along the cutting line centrally thereof, after which manual pressure is applied to the glass upon opposite sides of the glass breaker with the result that the glass will break evenly along the cutting line.

In the operation of the glass breaker, its top surface 41 which is perfectly flat, is positioned directly below the glass G to be broken.

As a part of the present invention, means are employed also for anchoring the straight edge to the glass or other surface, as desired. For this purpose there are provided a series of longitudinally spaced flexible suction cups 75

45. In order to accommodate these suction cups, a series of longitudinally spaced rectangular apertures 42 are formed through the bottom surface 13 of the body in order to cooperatively receive the suction cup holders 43, which are anchored to the body by a series of screws 44. The suction cup 45, preferably constructed of rubber, depends below the suction cup body 43, and below the undersurface of the straight edge body for cooperative retaining engagement with the top of the glass G, fragmentarily shown for example, FIGS. 6-7.

The upright release plate 47 is guidably positioned through a cylindrical extension 46 of the suction cup and projects thereabove. The release arm 48 has a bifurcated end, as shown in FIG. 5, which is pivotally mounted at 49 over the top surface of the release strip 47, and includes the cam surfaces 50, which cooperatively engage the top of the extension 46. Accordingly, when it is desired to remove the straight edge from the glass or other surface, the handle 48 is tilted so that the cam 50 operatively engages the extension 46 for breaking the seal between the glass and the suction cup 45 and to facilitate removal of the straight edge therefrom.

It is contemplated as a part of the present invention the straight edge may be in the form of a ruler. For this purpose, an elongated strip of material 51 with indicia 52, is mounted along and adjacent one of the edge strips 18 and extends throughout the length of the straight edge. For this purpose there may be employed indicia strip 51, of a plastic or other durable material, and which has a pressure adhesive undersurface as indicated at 53 by which the indicia strip may be rolled onto or otherwise mounted upon top surface 12 of the body, as best shown in FIGS. 5 and 7.

It is contemplated, of course, that an additional indicia strip 51 may be provided upon the straight edge upon its opposite edge adjacent the other edge strip 18. By this construction, the straight edge could be manufactured without the indicia strip and the indicia strip applied where requested, or required.

It is believed that the straight edge such as might be used in wall paper hanging, or in the cutting of linoleum, might be improved with the use of the said indicia strip. Also such indicia strip is commonly used in marking and cutting glass.

It is contemplated as a part of the present invention that the said removable nylon edge strip may be incorporated into other drafting instruments, other than a straight edge, as for example the T-square 54 shown in FIG. 8. Here the elongated, preferably extruded metal body 55 corresponding to body 11 of FIG. 3 also has mounted along its opposite edges the removable edge strips 18, corresponding to the edge strip above described in connection with FIGS. 3 and 4, and which construction in detail is not repeated.

The conventional transverse plate 56 along one edge has laterally projecting tongue 57 intermediate its length, which is snugly projected into one end of a body 55 of the T-square and suitably secured thereto, as by fasteners 58. Alternately, fasteners could be omitted, if desired, and the tongue 57 otherwise frictionally projected and secured within one end of the body 55 and T-square 54.

The present invention may also be incorporated into a right angle square, or other drafting instrument, as shown in FIG. 9. For this purpose, the elongated body 60 corresponding to the body 11 of FIGS. 3 and 4 has mounted on at least its outer edge the elongated nylon edge strip 18, as above described. A right angular body 59 of the same construction, engages and is suitably secured at one end to one end of the body 60, as at 62, and is suitably secured thereto. An angular reinforcing strip 61 extends between the body elements 59 and 60 and is suitably secured thereto at its ends. The body member 59 may also have mounted thereon a removable nylon

edge strip 18 of the same construction as above described.

Having described my invention, reference should now be had to the following claim.

I claim:

A straight edge comprising an elongated hollow body formed by extrusion of aluminum whereby it is rigid and inflexible, and having flat top and bottom surfaces and opposed sides formed of elongated undercut grooves whose edges also are rigid and inflexible;

10

edge strips having rabbeted formations cooperating with and interlocking such strips in the undercut grooves of the body and formed of a rigid, unyielding non-wearing plastic material such as nylon; said edge strips being of a height greater than said 15 body and projecting outwardly of its respective top and bottom surfaces; the ends of the body being open; closures for said open ends comprising blocks of compressible elastic material frictionally and removably held in the body ends by the elasticity of such material; said blocks having portions overlying the ends 20 of the edge strips and holding them in the body against longitudinal movement relative to said body; said edge strips being insertable into and readily re- 25

movable from the body grooves by relative longitudinal movement of the edge strips and the body, such movement taking place only when the blocks are not in body closing position; said blocks being readily insertable into and removable from said body ends.
